W. F. ZIEGLER.

POUNTAIN BRUSH.

APPLICATION FILED MAY 6, 1912.

1,080,669.

Patented Dec. 9, 1913.

UNITED STATES PATENT OFFICE.

WILLIAM FLOYD ZIEGLER, OF LOS ANGELES, CALIFORNIA.

FOUNTAIN-BRUSH.

1,080,669.

Specification of Letters Patent.

Patented Dec. 9, 1913.

Application filed May 6, 1912. Serial No. 695,424.

To all whom it may concern:

Be it known that I, WILLIAM FLOYD ZIEGLER, a citizen of the United States, residing at Los Angeles, in the county of Los Angeles and State of California, have invented a new and useful Fountain-Brush, of which the following is a specification.

This invention relates to fountain brushes and more particularly to that class of brushes in which a constant flow of water is delivered to a fountain reservoir to saturate the brush when the same is being used, such class of brushes being intended primarily for washing show windows, floors and other similar surfaces, and it is a prime object thereof to provide an improved fountain brush construction in which the cleansing fluid is delivered adjacent to the brush and not through the brush back, thus obviating the perforation of the brush back for the exit of water to the brush.

A further and important object is to provide a fountain brush construction by means of which different styles of brushes or other cleaning and polishing devices may be readily attached thereto, or removed therefrom, thus enabling the utilization of various styles of cleansing and polishing devices with a single holder.

I accomplish these objects by means of the device described herein and illustrated in the accompanying drawing in which,

Figure 1 is a side elevation of my improved brush showing a portion of the handle attaching means. Fig. 2 is an end elevation of my improved brush. Fig. 3 is a central transverse sectional view of my brush and handle attaching means, taken on line 3-3 of Fig. 1. Fig. 4 is an inverted plan view of my brush mechanism with the brush removed therefrom. Fig. 5 is an end elevation of my detachable brush. Fig. 6 is a transverse sectional view of the inlet nozzle taken on line 6-6 of Fig. 2. Fig. 7 is an end elevation of another form of brush that may be used in my holder.

Referring more particularly to the drawing 10 designates a preferably rectangular metallic brush holding structure, the upper part thereof being hollow and formed into a water receiving chamber or fountain 11. The under face 12 of the brush holding structure 10 is recessed to form a brush receiving chamber 13 as clearly shown in Figs. 3 and 4 of the drawing. The longitudinally extending parallel edges 14 and 15 of the

brush holding chamber are provided on their under face with a series of apertures 16 which deliver the water from the fountain chamber 11 to the surface of the work on which the brush is being used. The oppositely disposed sides of the brush holding structure adjacent to the edges 14 and 15 are provided with flanges 17 and 17^a, these flanges projecting into the brush receiving chamber 13 and extending the entire length thereof. These flanges are provided for the purpose of supporting the back of a brush 19, the edges 20 resting on the flanges 17 and 17^a as clearly shown in dotted lines in Fig. 2 of the drawing. One end of the brush holding structure is provided with an integral end wall 21 as best shown in Fig. 3 and Fig. 4 of the drawing, this wall limiting the further movement of the brush 19 when inserted in the holder.

The upper portion of the fountain chamber 11 is provided with a longitudinally extending partition 22 and provided with a valve seat 23, a valve stopper 24 adjustably mounted in the upper wall of the brush holding structure seating therein. By means of this partition and valve I am enabled to direct the water flowing through the chamber 11 through the perforations 16 so that the water delivered therefrom will be in advance of the movement of the brush on the surface on which it is used. It will of course be observed that by unseating the valve 24 water may be directed through the fountain chamber 11 through both lines of perforations 16 if found desirable.

Centrally disposed in the upper wall of the brush holder 10 is an exteriorly threaded nipple 25 through which water is delivered to the fountain chamber 11. Adjustably secured to nipple 25 is a hollow curved socket member 26 which may be held in an adjusted position by means of a set screw 27. Mounted in socket 26 is the lower end of a curved distributing member 28 which will be readily seen from an inspection of Fig. 3 of the drawing and may be adjusted to any angle desired, a set screw 29 holding the same in an adjusted position. Adjacent to the upper interiorly threaded end of member 28 is disposed transversely therein a partition 30 provided with apertures 31. Adjustably attached to member 28 at the upper end thereof is a handle 32 exteriorly threaded at its lower end and provided with a centrally disposed aperture 33 as best

shown in Fig. 3 of the drawing. This handle may be of any material that is found desirable and by locating the aperture 33 in the center of its lower end it will be noted 5 that the water which passes through handle 32 from a flexible hose 33' attached to the outer end thereof may be controlled by merely screwing the handle into the socketed end of member 28 so that the aperture 33 is 10 forced against the transverse wall 30 of member 28 as best shown in Fig. 3 of the drawing. In this view the lower end of handle 32 is away from the transverse wall 30 permitting a free and unrestricted flow 15 of fluid from the handle through member 28 to the fountain chamber 11 and from thence through the apertures 16 to the surface on which the brush is being used. The flexible tubing may be connected to a source 20 of water supply such as a faucet in the usual manner, and by reason of the valve structure at the end of the handle the flow may be controlled at all times during the operation of the brush.

25 In order to secure the brush in rigid relation to the brush holding structure on the end opposite to wall 21 I have provided a door structure 34 which is secured thereto by means of a hinge 35, the end opposite to 30 the hinge being provided with an eye 36 which is adapted to be engaged by a hook or other fastening means 37 secured to one of the side walls of the brush holding structure. After the brush has been inserted in 35 its receiving chamber 13 the door is swung to and the latch pulled into position, thus forming an interior structure and preventing all movement of the brush held in the holder.

40 In Fig. 7 of the drawing I have illustrated a form of polishing device in lieu of the brush structure which consists of a back 38 provided on the under face thereof with a mop structure 39 which may be used in mopping floors or other surfaces or in polishing 45 windows or floors that have been cleansed.

It will be noted that almost any form of brush may be used such as brushes with comparatively long and stiff bristles as well as 50 those containing fine and soft bristles, together with mops and polishing pads, thus enabling a person to utilize a number of devices of a different character with a minimum of expense, the brushes and other devices being of a relatively low cost in comparison with the brush holding structures.

55 What I claim is:

1. A fountain brush comprising a hollow metallic brush holder, provided on two of 60 its oppositely disposed edges with fluid outlets, said brush holder being provided in its upper wall with a fluid inlet, a hollow ad-

justable handle telescopically secured to said brush holder in communication with the fluid inlet of said holder, said hollow handle 65 being adapted for the passage of a fluid therethrough to the hollow brush holder, and a rotative fluid cut-off mounted within said handle and operated by a rotation thereof, means to control the fluid supply 70 flowing through said handle, the outer end of said handle being connected to a source of fluid supply.

2. A fountain brush comprising a metallic brush holding structure provided with a 75 fluid chamber and having on the lower walls of its oppositely disposed sides fluid outlets, a hollow exteriorly threaded nipple secured to the top wall of said brush holder and forming a fluid inlet thereinto, a hollow 80 curved socket adjustably secured to said nipple, a hollow curved member mounted in said socket and secured in adjustable relation thereto, a hollow handle movably secured to said member mounted in said socket 85 and means to control the flow of fluid passing through said hollow handle to said brush holding structure.

3. A fountain brush comprising a rectangular metallic brush holding structure provided with a fluid chamber and having fluid outlets leading therefrom, a brush member detachably secured to said holder, said holder being further provided with a fluid inlet in the top wall thereof, an adjustable 90 hollow handle secured to said brush holder and adapted to deliver a fluid from a source of supply through the fluid inlet to said chamber, a longitudinally extending partition mounted in the interior of said chamber 95 and forming a plurality of compartments, and valve means mounted in one of the walls of said chamber to control the supply of fluid to one of said compartments in said chamber.

100 4. A fountain brush, comprising a fluid receiving chamber provided with a fluid inlet and having a plurality of fluid outlets leading therefrom, a brush detachably secured to said chamber, a hollow handle for 110 conveying fluid to said chamber adjustably and telescopically connected to the inlet of said chamber, means to adjust the angle of said handle with respect to the fluid receiving chamber, and means to control through 115 said handle the flow of fluid to said chamber.

In witness that I claim the foregoing I have hereunto subscribed my name this 24th day of April, 1912.

W. FLOYD ZIEGLER.
